UNITED STATES PATENT OFFICE.

WILLIAM Y. SCHMUCKER, OF READING, PENNSYLVANIA.

INK-GRINDER.

SPECIFICATION forming part of Letters Patent No. 313,246, dated March 3, 1885.

Application filed October 4, 1884 (No model.)

To all whom it may concern:

Be it known that I, WILLIAM Y. SCHMUCKER, of Reading, in the county of Berks and State of Pennsylvania, have invented a new 5 and Improved Ink-Grinder, of which the following is a full, clear, and exact description.

The object of my invention is to provide a simple, efficient, and inexpensive machine for grinding or "rubbing up" india-ink to proper 10 liquid consistency for the use of architects, engineers, draftsmen, and others.

The invention consists in an ink-grinder constructed with a saucer-clamp and a chuck adapted to hold the solid ink cakes or sticks, 15 and to be revolved above the saucer, and having means to feed the ink-cake downward as it wears away by friction on the saucer.

The invention consists, also, in particular constructions of parts of the ink-holding chuck, 20 to facilitate holding ink-cakes of varying shapes and sizes, and in other details of construction, all as hereinafter fully described and claimed.

Reference is to be had to the accompanying 25 drawings, forming part of this specification, in which similar letters of reference indicate corresponding parts in all the figures.

Figure 1 is a sectional side elevation of my 30 improved ink-grinder. Fig. 2 is a plan view in section on line *x x*, Fig. 1, and drawn to a larger scale. Fig. 3 is an enlarged vertical sectional elevation of the ink-holding chuck or head; and Fig. 4 is a sectional plan view of the chuck, taken on the line *y y*, Fig. 3, and 35 in larger size.

The letter A indicates the base-plate of the machine, and B a standard, which is fastened to the base by screws or bolts *b*, passing through the forked arms *b b* of the standard; 40 and C is a bent arm, which is shown cast in one piece with the base A, but which may be made separate, and be connected with the base at *a* by screws or other means. The upper end or part of the arm C has a screw or bolt end, *c*, fixed to it, which passes through the standard B, and receives a nut, *c'*, to hold the parts together, to constitute a light, strong frame to support the operating parts of the machine.

50 D is the horizontally-rotating ink-holding chuck or head, which is journaled at its upper end in a bearing, C', of the arm C, and has

fixed to it the bevel gear-wheel E, which meshes with a bevel gear-wheel, F, fixed to a shaft, G, which is journaled in a bearing, *g*, on the standard B, and has fixed to it the crank H, by turning which motion may be given to the chuck D. The chuck D has an enlarged lower end or foot, D', which is apertured vertically at I, and in one side wall of the aperture is formed the rounding recess J, which comes opposite to a like recess, K, formed in the face of the clamp block or gib L, which has a head, *l*, by which it hangs loosely within the aperture I from the upper face of the foot-piece D'. 60 Screws M M are threaded through the side wall of the foot-piece D', and bear by their inner ends against the inner face of the clamp-block L, to hold the cake or stick N of ink between the block L and the opposite wall of the aperture I. The recesses J K allow round or polygonal sticks of ink to be clamped by them, and the adjoining or opposing faces *j j* and *kk* of the foot-piece D' and block L are for holding square or rectangular sticks or cakes of 65 ink; hence the chuck D is adapted to hold sticks or blocks of ink of any usual shape or size.

Above the aperture I, and on the chuck-body, is a threaded lug, O, into which the screw P 80 is fitted, so as to be turned down on the end of the cake N of ink or onto a wooden block, R, placed between the ink and the foot-plate *p* of the screw. The last piece or remnant of the ink-cake may be glued to the end of a block, 85 R, of suitable shape, so that as the block is forced downward by the screw P all the ink may be ground or rubbed up, thus avoiding waste of the ink. The ink-saucer S is held by a clamp consisting of a stationary jaw, T, cast 90 with or fixed to the base A, and a movable jaw, U, to which one end of a screw, V, is swiveled, said screw being threaded through a bearing or nut at *v* in the arm C, and having a suitable head by which to turn it in or 95 out, for clamping the saucer S firmly and directly below the chuck D. I show the saucer S made with an overhanging rim portion having a tongue, *s*, which enters grooves in the faces of the clamp-jaws T U; but the saucer 100 may have any suitable shape or size, and the clamp-jaw faces be made to correspond, as will readily be understood. I prefer to connect the pinion E to the chuck D and the gear-

wheel F and handle H to the shaft G by means of screws W, which enter the squared ends of the journals or shafts on which the wheels and handle are fitted, and bear by their heads *won* 5 the outer faces of the wheels and handle, (see Fig. 1;) but the gear-wheels and handle may be held to place in any other approved way.

In operating the machine the saucer S, from which the liquid ink is to be dipped by the draftsman's pen, is charged with water or other liquid, and clamped by the jaws T U under the chuck D, in which the stick of ink N is held by the block L and screws M, so that the ink N will not shake or tremble in the chuck, but 5 may be forced downward to the saucer S, as it wears away by the friction on the saucer as the chuck D is revolved, by turning the crank H by one hand, the other hand being free to feed the ink downward, as required, by turning the screw P.

It is evident that the solid ink N may be ground and the liquid ink in the saucer be brought to the proper consistency in a very short time, and without soiling the fingers or 5 danger of spattering the liquid ink about on the table or work, thereby not only largely economizing time, but avoiding waste of the ink.

Having thus described my invention, what I claim as new, and desire to secure by Letters Patent, is—

1. An ink-grinder constructed with a saucer-clamp, a chuck adapted to hold the solid ink-cake and fitted to revolve above the clamped 5 saucer, and having means to feed the ink-cake downward as it wears by friction on the saucer, and means to rotate the chuck, substantially as herein set forth.

2. The combination, in an ink-grinder, of a base-plate, A, frame B C, saucer-clamp T U 40 V, ink-holding chuck D, gear-wheels E F, shaft G, and handle H, all substantially as shown and described.

3. In ink-grinders, the ink-holding chuck D, constructed with a foot-piece, D', apertured at 45 I, a clamp-block, L, screws M, and a screw, P, adapted to feed the ink through the aperture I, substantially as shown and described.

4. In ink-grinders, the ink-holding chuck D, constructed with a foot-piece, D', apertured at 50 I, a clamp-block, L, and screws M, and said foot-piece and clamp-block having opposite rounding recesses J K and flat faces *j k*, as specified, and a feed-screw, P, substantially as shown and described.

5. In ink-grinders, the clamp-block L, made with an upper flange, l, to suspend the block within the aperture I of the chuck, and a rounded recess, K, and flat faces *k k*, substantially as shown and described.

6. In ink-grinders, the combination, with the ink-holding chuck D, having a foot-piece, D', apertured at I, and the clamp-block L, screws M, and feed-screw O, of the block R, interposed between the feed-screw and the ink-cake 65 N, substantially as shown and described.

7. In ink-grinders, the saucer-clamp constructed with a fixed jaw, T, a movable jaw, U, and a swiveled screw, V, and arranged below the ink-holding chuck D, substantially as 70 shown and described.

WM. Y. SCHMUCKER.
